(57) **CLAIM**

The ornamental design for a light fixture including heat sink and elongated driver housings, as shown and described.

DESCRIPTION

FIG. 1 is an upper front perspective view depicting a light fixture including heat sink and elongated driver housings; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; and, FIG. 8 is a lower rear perspective view thereof.

The details shown in broken lines in the figures form no part of the claimed design of the light fixture including heat sink and elongated driver housings. The details shown in dot-dash broken lines in the figures define the bounds of a portion of the claimed design of the light fixture including heat sink and elongated driver housings and form no part of the claimed design. The figures include surface shading, which represents contour and not surface ornamentation.
